UNITED STATES PATENT OFFICE.

HANS C. BEHR, OF SAN FRANCISCO, CALIFORNIA.

CENTRIFUGAL PUMP.

SPECIFICATION forming part of Letters Patent No. 546,219, dated September 10, 1895.

Application filed December 3, 1894. Serial No. 530,738. (No model.)

To all whom it may concern:

Be it known that I, HANS C. BEHR, a citizen of the United States, residing in the city and county of San Francisco, State of California, 5 have invented an Improvement in Centrifugal Pumps; and I hereby declare the following to be a full, clear, and exact description of the same.

My invention relates to the class of centrifugal pumps with inlets at one side only; and it consists in the novel construction and arrangement of parts hereinafter fully described and specifically claimed, the object of which is to balance or relieve the pressure on 10 the impeller or runner, tending to displace it axially or cause end friction against the collars on the impeller-shaft.

Referring to the accompanying drawings for a more complete explanation of my invention, Figure 1 is a section of the pump through the center line of the impeller-shaft. Fig. 2 is a section in a plane at right angles to the center line of impeller-shaft.

The impeller of the pump is an incased one, 25 the casing consisting of one side A', having a central inlet-opening, and curved outwardly at its center toward a cylindrical form to meet and join the inlet G of the pump. The other side A² of the impeller-casing extends to the center, where it is formed into or joins the hub P, secured to the impeller-shaft E, which is mounted in a suitable bearing in the exterior housing or shell A. The two sides A' and A² of the impeller are connected by suitable 30 35 radial blades, such as the long ones B, here shown, and the short intervening ones C. Holes O O near the hub P permit of the equalization of the pressure on the central part of the casing side A². A conoidal shield

40 U, of a diameter approximately the same as the inlet-opening to the impeller in the side A', covers the inner central part of the side A², with its openings O O, and comes into proximity with said side at the periphery of 45 the shield, as shown at K².

The function of the shield U may be described as follows: In ordinary single-inlet pumps it is a part of the impeller and revolves with it. In this case it is subject, on 50 the side near the housing, to the entire pressure due to the centrifugal head existing at the periphery of the runner, which pressure is

obviously transmitted to the space between outside of runner and shell, as there is no packing at the periphery of runner. On the 55 inner side of the runner the pressure is zero at the center and increases outwardly in proportion to the square of the radius, so that there exists an over pressure, with the ordinary single-inlet runner pressing it in one 60 direction, which pressure has to be taken up by collars against journals. These bearings are very liable to heat and grind. By having the holes O O the runner is relieved of this side pressure; but the center of the runner 65 thus apertured and subject to pressure needs the bracing and support of the shield U.

The impeller sides A' A² come into proximity with the outer housing or shell only at the inlets and outlets on said impeller, as is shown 70 at the points J and K'.

The shield U is stationary and is secured upon a rod V, which supports it axially from the hub Z of the web or bridge Z², formed with or secured in the inlet-piece G.

Instead of the construction just described, 75 the elbow G² may be directly attached to the pump-housing and the rod extended through its curved part, as shown in dotted lines by V².

The shield U is maintained in a central position by the enlarged extension W of the rod V, which said extension extends into the hub P of the impeller-casing side A², said hub revolving on the extension, which, with its rod V and shield U, remains fixed and non-rotating. 80 85 The gradual curvature of the surface of the shield U leads the liquid with easy sweep into the impeller.

In order to lubricate the extension W, the oil-cup Y, communicating with channels X 90 and X², leading to W, is provided.

I is the discharge-duct of the pump, M the flaring nozzle, and N the discharge-pipe.

Having thus described my invention, what I claim as new, and desire to secure by Letters 95 Patent, is—

In a centrifugal pump, the combination, of a casing having one side A' with a central inlet opening, and curved outwardly at its center to meet and join the inlet pipe of the pump, 100 and having its opposite side A² extended to the center where it is formed with a hub, with holes in said side near the hub to equalize the pressure on the central part of the said

casing side A², a conoidal shield of a diameter approximating the same as the inlet opening in the side A¹, covering the central part of the side A² and its holes, and with its periphery in proximity with said side, alternating long and short radial vanes connecting said sides, a stationary rod for supporting the shield axially, a web or bridge formed with or secured in the inlet of the pump, said rod having an enlarged extension which enters

the hub of the impeller whereby the shield is maintained in a central position, a flaring discharge nozzle and a discharge pipe communicating therewith.

In witness whereof I have hereunto set my hand.

HANS C. BEHR.
